UNITED STATES PATENT OFFICE

2,425,430

BUNDLING MACHINE

Nathan C. Heaton and Stephen A. Sarnecki, Chicago, Ill., assignors to Montgomery Ward & Co., Incorporated, Chicago, Ill., a corporation of Illinois

Application September 16, 1943, Serial No. 502,624

10 Claims. (Cl. 100—31)

1

This invention relates to a bundling machine and more particularly to a machine adapted to tightly bundle together a plurality of elongated objects such as rolls of wallpaper for the purpose of facilitating the tying together of the objects into a secure bundle, adapted for wrapping for shipment thereafter.

Heretofore in bundling a plurality of elongated objects for shipment it has been the practice to manually arrange the objects parallel to one another, to thereafter manually arrange the objects in a generally cylindrical shaped bundle and thereafter by the application of a cord tying member arranged around the girth thereof to draw the objects tightly together and at the same time securely tie them into a permanent bundle. In applying proper tension to the binding cord manually to draw the objects into a tight bundle, it has been found that the rough cord soon results in injury or laceration of the operator's hands, particularly where such operator arranges a large number of such bundles during the course of a given period.

It is an object of the present invention to relieve the operator of the manual strain of drawing a plurality of elongated objects into a tightly arranged bundle and to provide mechanism for tightly bundling a plurality of such objects so that tying cords can be applied to the bundle without the necessity of applying any particular tension to the cord itself.

Another object of the invention is to provide a machine for tightly gripping and bundling a plurality of elongated objects such as rolls for wallpaper without injuring the objects but at the same time bundling them sufficiently tight so that one or more cords may be loosely tied around the bundle to the end that upon release of the bundling pressure the cords may secure the objects in a unitary unit adapted for packaging.

A further object of the invention is to provide a machine of the type described capable of adaptation to resulting bundles of widely varying size.

The above and other novel features of the invention will appear more fully hereinafter from the following detailed description when taken in conjunction with the accompanying drawings. It is expressly understood, however, that the drawings are employed for illustration only and are not designed as a definition of the limits of the invention, reference being had for this purpose to the appended claims.

In the drawings, wherein similar reference marks refer to similar parts throughout the several views:

2

Figure 1 illustrates a longitudinal vertical section of the apparatus, the section being taken close to one side of the machine so as to provide an elevational view of the mechanism of the machine, the section being taken substantially on the plane 1—1 appearing on Figure 5 hereinafter referred to.

Figure 2 is a fragmentary side view of a portion of the mechanism illustrated in Figure 1 showing a step in the operation of the apparatus.

Figure 3 is a further longitudinal vertical sectional view similar to Figure 1 and showing the apparatus positioned in a third step of the operation thereof.

15 Figure 4 is a transverse horizontal section taken substantially on the plane 4—4 of Figure 1 and illustrating the motivating cylinder for the apparatus.

Figure 5 is a top plan view of the apparatus in the position illustrated in Figure 1.

20 Figure 6 is a horizontal section of the apparatus taken substantially on plane 6—6 of Figure 1 and illustrating the winding drum and associated rotating elements in top plan.

Figure 7 is a detailed view of the control valve and a safety interlock feature and is taken substantially on the line 7—7 of Figure 5.

25 Figure 8 is a section taken through a portion of the framework and an end of the wrapping strap, substantially on the line 8—8 of Figure 5.

Figure 9 is a section taken through a portion of the framework and an end of the wrapping strap, substantially on the line 9—9 of Figure 5.

30 Referring to Figure 1 there will appear a framework comprising uprights 10 and 11 and substantially horizontal brace members 12 and 14 which in turn support a pair of arcuate basket

35 forming arms 16 and 18. A plurality of objects such as rolls of wallpaper, rolled newspapers or the like are illustrated at 20 resting upon the arcuate arms 16 and 18 forming the basket. The frame is additionally provided with drum supporting horizontal frame members 22 and 24

40 extending between the uprights 10 and 11 of the frame and cylinder supporting members 26 and 28 extending parallel to the members 22 and 24 at a position lower in the frame. The arcuate basket forming members 16 and 18 are suitably

45 spaced to support the objects adjacent their ends so as to provide an intervening space for bundling straps which are mechanically operated as will appear hereinafter. The basket is provided with

50 transverse members 30 and 32 on one side thereof and the other side is left open for facility in loading and operating the apparatus. The frame is provided with a transverse member 34 immediately beneath the basket upon the open side

55 thereof.

In order to bundle a plurality of objects 20, positioned within the basket, and apply suitable pressure thereto to facilitate the placing of a cord around the bundle and the tying of the cord, crossing straps 36 and 38 of leather or other suitable material are provided. The strap 36 is centrally positioned between the basket arms 16 and 18 and is provided with a handle at one end generally indicated by the reference character 39 and is secured at its other end 40 upon the periphery of a drum 42 freely rotatable on the shaft 76 journaled in the frame members 22 and 24. The strap 38 as will be seen in Figure 5 is divided, half of the strap being located on either side of the strap 36. The divided portions of the strap 38 are secured to the transverse member 34 by riveting or otherwise securing the same to a transverse plate 44 which is adjustably secured to the angle member 46 welded to the transverse member 34. Adjustment of the plate 44 by means of the slots 48 and the screws 50 permits the equal tensioning of the divided portions of the straps 38. The other ends of the divided portions of the strap 38 are loosely laid across the bottom of the basket formed by the basket forming arms 16 and 18 and are secured together at their free ends by a transverse semi-circular section handle bar 52 which is adapted to be hooked over the transverse member 30 when the apparatus is in position for loading.

Secured to the strap 38 and the handle bar 52 is a transverse, reverse bent, channel hook sectioned member 54 which is adapted to engage a similar channel hook sectioned member 56 secured to the strap 36 adjacent to the handle thereof, as may be seen in Figures 2 and 7, it being appreciated that the strap 36 may be drawn around a bundle of elongated units 20 by reason of the rotation of the drum 42 from the position shown in Figure 1 to that shown in Figure 2.

For the purpose of applying a slight initial tension to the strap 36 so that the same may be readily extensible through wrapping or unwrapping upon the drum to any desired degree to embrace varying sized groups of objects to be bundled together, the drum is provided with a hub extension 58 around which is wrapped a strap 60 secured at one end to the hub as at 61, its other end being secured to a coil spring 64 extending to the frame. It will appear that the spring 64 and strap 60 constantly urge the drum 42 to rotate in a clockwise direction to lightly tension the strap 36 and take up slack.

To apply bundling tension to the straps 36 and 38, power means are provided to rotate the drum clockwise under a substantially uniform torque. For this purpose there is provided a fluid pressure cylinder 62 supported from the frame members 26 and 28, and a reciprocatable piston 64 therein having a piston rod 66 provided with a crosshead 68 and parallel guide rods 70. Through a link 72 connected to the crosshead 68, a crank arm 74 is rotated by movement of the piston 64, the crank arm being secured to shaft 76 upon which the drum 42 freely rotates. An over-running clutch or ratchet and pawl 78 and 80 respectively, are provided whereby upon rotation of the crank 74 in a clockwise direction, the drum may be caused to rotate. Since the movement of the crank arm 74 is restricted to a relatively small angle, and since it is desirable to apply a substantially uniform tension when the bundling operation is performed, initial tension in the strap 36 is taken up by the spring 64 and

the belt 60 heretofore described. In order to completely and positively disengage the pawl from the ratchet during the initial slack take up, the pawl 80, pivotally mounted upon the arm 74 and ordinarily resiliently urged into engagement with the ratchet 78, is caused to assume a disengaged position by reason of a cam-like engagement with a cam 83 carried on a frame supported arm 82 when the crank arm 74 is in the initial or rest position. The arm 82 may also act as a limit to restrict the angular movement of the crank 74 upon return to the position shown in Figure 1 thereof. A return spring 84 extending between the crosshead 68 and a fixed bracket 86 is adapted to return the piston and the crank arm to the initial position upon the relief of fluid pressure within the cylinder.

To control the application of pressure to the cylinder from a source of fluid pressure, a valve 88 is provided, the valve having a vertically extended rotatable operating rod 90, provided with a handle 92 at its upper end located adjacent to the transverse frame member 34 and adapted to be engaged by a hook 94 (see Figure 1) on the under side of the strap 36 adjacent the bundle engaging end thereof. It will thus appear that tension upon the strap 36 will tend to maintain the valve in an off position by its engagement with the control handle 92 and that the valve 88 will be moved to open position only by clockwise rotation of the control handle 92 as shown in Figure 5. The valve is so constructed and arranged as to permit the cylinder to exhaust when the source of fluid pressure is cut off, as will be well understood in the art.

The operation of the apparatus will be understood from a consideration of the foregoing description. Briefly, however, a plurality of objects such as rolls of wallpaper as indicated at 20 are placed within the basket arms 16 and 18 with their ends extending slightly beyond the arms 16 and 18. Thereafter the strap 36 is unhooked from the valve handle 92 and wrapped around the group of objects or wallpaper rolls, as the case may be, and hooked to the end of the divided strap 38 through interengagement of the hooks 56 and 54. Sufficient slack for this operation is provided by the counterclockwise free rotation of the drum 42 against the light tension of a spring 64. At this time the end of the divided strap 38 may be unhooked from its normal resting position across the basket transverse member 30 and the bundle allowed to freely assume the position shown in Figure 2. Thereupon the valve 88 is operated admitting compressed air into the cylinder 62 from a source of previously predetermined pressure. The piston is thereupon driven from right to left rotating the crank arm 74 clockwise. Upon initial movement of the crank arm away from the bracket 82 the pawl is disengaged from the cam 83 and is resiliently urged into engagement with the ratchet 78, causing the drum 42 to rotate and tension the strap 36 in an amount proportional to the pressure of the fluid within the cylinder. This causes the bundle of articles to be compressed and to generally assume a shape cylindrical in contour at which time a string or cord may be placed around either end of the bundle and tied. It will be understood that in applying such cord no tension whatsoever need be used and in fact the cord may be somewhat loosely applied to the bundle while the same is being tied, for the tension upon the straps 36 and 38 is such as to compress the bundle to such a degree that

when the pressure is relieved the bundle will expand into snug engagement with the binding cords thereby providing a bundle properly tied under a predetermined degree of pressure. Upon completion of the tying of suitable cords around the bundle the valve is closed, the cylinder exhausted and the pawl bearing arm 14 returned to its initial position whereupon the pawl 80 is positively disengaged from the ratchet 78. The bundle may thereafter be removed from the embrace of the straps 36 and 38 by uncoupling the hooks 54 and 56.

It will appear that with such an apparatus, a uniform, proper and predetermined bundling pressure may be applied to each bundle with the result that under no circumstances will the articles of which the bundle is composed be injured, provided the proper pressure has been selected. It will also appear that by controlling the pressure that is to be provided in the bundling operation the tension of the cords, which are firmly placed around the bundle, and which finally secure the bundle together, after the bundling pressure is released, will be applied with a tension properly selected to avoid injury to the objects in the bundle which are in immediate engagement with the cords. It will also appear that if desired any suitable wrapping material may be wrapped around the group of objects prior to embracing the objects with the straps for the bundling operation, which wrapping material may safeguard the later applied cords from injuring the bundle objects. With the apparatus set forth it will appear that the operator in applying the cords around the bundle might apply no tension whatsoever to the cords prior to tying and for this reason a single operator may bind a plurality of bundles without danger of laceration of the hands since the cord need only be lightly gripped in arranging the same upon the bundle and in tying the knot. It will of course appear obvious that bands of any suitable sort may be employed in place of cords and that in the normal operation of the apparatus the application of the bands to the bundle will be facilitated in that the bands may be applied while in slackened condition, and the ends joined while free of tension.

While a single embodiment of the machine has been described and illustrated it is to be understood that the invention is not limited thereto but may be altered in various ways without departing from the spirit of the invention as would be well understood by those skilled in the art. Reference thus is had to the appended claims for a definition of the limits of the invention.

What is claimed is:

1. In a bundling machine the combination of a bundle-receiving basket, crossed flexible bundle-compressing members adapted to lie along the lower outline of the basket, means for securing the bundle-engaging ends of said members together after passing around opposite sides of a bundle resting in said basket, means for applying sufficient initial tension to one of said members to take up slack independently of the size of said bundle, and power-operated means for applying uniform bundling tension to said one of said members.

2. In a bundling machine, a bundle receiving basket, crossed flexible members adapted to lie along the lower outline of the basket, means for securing the bundle engaging ends of said members together after passing around opposite sides of a bundle resting in said basket, slack take up means, power means having a limited movement

less than the slack take up means for applying a bundling tension to one of the members adjacent the other end thereof and clutch means for transmitting power from said power means to said one of the members through said slack take up means.

3. In a bundling machine, a bundle receiving basket, crossed flexible members adapted to lie along the lower outline of the basket, means for

10 securing the bundle engaging ends of said members together after passing around opposite sides of a bundle, initial tension means to take up slack in said members, means for applying a bundling tension independent of the size of said bundle to the other end of one of said members including

15 limited movement power means, and means for applying the power means to said member subsequent to the operation of the slack take up of the initial tension means.

20 4. In a bundling machine, a bundle supporting basket, crossed flexible members adapted to lie along the base of the basket, means for securing the bundle engaging ends of said members together after passing around opposite sides of a bundle

25 arranged within said basket, whereby tension upon the opposite ends of said members will apply a squeezing pressure upon the bundle, resilient means for eliminating slack associated with one of said members, and limited movement power means adapted at will to be connected to said one of said members to apply a predetermined squeezing pressure to the bundle.

30 5. In a bundling machine, a bundle receiving basket, composed of spaced apart bundle receiving supports, a pair of crossed flexible bundling members adapted to lie along the base outline of said supports and therebetween, means for connecting the free ends of said members together after passing the members around the opposite

35 sides of a bundle, means for applying sufficient tension to the other end of one of said members to take up the slack in said member, said means comprising a drum upon which said one of said members is wrapped and power-operated means for engaging said drum at any slack take up position and applying a uniform fixed bundling torque thereto.

40 6. In a bundling machine, a bundle-receiving basket thereon having spaced bundle-supporting arms, crossed flexible members adapted to lie along the base of said basket and between said arms, means for securing the bundle-engaging ends of said members together after passing around opposite sides of the bundle, means for

45 securing the other end of one of the members to the frame, a rotatable drum mounted within the frame, means for securing the other end of the other member to said drum, means for applying a light torque to said drum to apply initial tension to said other member, and power-operated means for applying a uniform bundling pressure to said other member, said last-mentioned means being coupled to said drum so as to effect its rotation irrespective of the position of the drum occasioned by the initial tensioning movement.

65 7. In a bundling machine, a frame, a bundle receiving basket thereon having spaced bundle supporting arms, crossed flexible members adapted to lie along the base of said basket and between said arms, means for securing the bundle engaging ends of said members together after passing around opposite sides of the bundle, means for securing the other end of one of the members to the frame, a drum mounted within the frame, and means for securing the other end of the other member to said drum, means for applying a light

torque to said drum for slack take up purposes, a fluid pressure cylinder and piston, a crank arm actuated thereby rotatable on a common axis with said drum, and ratchet means for transmitting movement of said crank arm to said drum.

8. In a bundling machine, a frame, a bundle receiving basket thereon having spaced bundle supporting arms, crossed flexible members adapted to lie along the base of said basket and between said arms, means for securing the bundle engaging ends of said members together after passing around opposite sides of the bundle, means for securing the other end of one of the members to the frame, a drum mounted within the frame, and means for securing the other end of the other member to said drum, means for applying a light torque to said drum for slack take up purposes, a fluid pressure cylinder and piston, a crank arm actuated thereby rotatable on a common axis with said drum, normally disengaged ratchet means for transmitting movement of said crank arm to said drum, and means for engaging said ratchet upon initial movement of said arm through its initial range of movement.

9. In a bundling machine, a frame, a bundle receiving basket thereon having spaced bundle supporting arms, crossed flexible members adapted to lie along the base of said basket and between said arms, means for securing the bundle engaging ends of said members together after passing around opposite sides of the bundle, means for securing the other end of one of the members to the frame, a drum mounted within the frame, and means for securing the other end of the other member to said drum, means for applying a light torque to said drum for slack take up purposes, fluid pressure means for rotating said drum and applying a greater torque thereto, manual means having an on and off position for controlling the flow of fluid to said fluid pressure means, and

means upon said other member for engaging said manual means when said members are disconnected, and adapted to hold said manual means in an off position by said slack take up.

5 10. In a bundle-wrapping machine of the type having a receptacle for holding elongated substantially cylindrical objects in horizontally disposed position and circumferentially bundle-enfolding tape-like bundling means arranged in crossed relationship, the improvement which comprises the combination of spring-actuated means for asserting a light preliminary tension upon said tapes so as to initiate the assembly of said cylindrical objects and final power-driven tensioning means adapted to increase the tension to a predetermined controlled bundling-tension, said latter means comprising a fluid-pressure cylinder and piston, and link-and-drum means connecting said piston with said final tensioning means.
